UNITED STATES PATENT OFFICE.

CHARLES W. GRAHAM, OF CRESTWOOD, NEW YORK, ASSIGNOR TO AMERICAN CAN COMPANY, OF NEW YORK, N. Y., A CORPORATION OF NEW JERSEY.

CAN-END-LINING MACHINE.

1,348,560.

Specification of Letters Patent. Patented Aug. 3, 1920.

Application filed March 29, 1916. Serial No. 87,390.

To all whom it may concern:

Be it known that I, CHARLES W. GRAHAM, a citizen of the United States, residing in Crestwood, in the county of Westchester and State of New York, have invented a new and useful Improvement in Can-End-Lining Machines, of which the following is a specification.

This invention relates in general to machines for applying can end liners to the flanges of shouldered can ends for the production of interfolded hermetic seams with flanged can bodies, and has for its object broadly the provision of a machine for applying ring liners previously cut and from a stack to can ends taken from another stack in an expeditious manner and without danger of damage to the liners.

A further object of the invention is the provision of such a machine which will operate efficiently and yet be of cheap and simple construction.

Other objects and advantages of the invention will be apparent as it is better understood from the following description when considered in connection with the accompanying drawing illustrating a preferred embodiment thereof.

On the drawings,

30 Figure 1 is a plan view of a machine embodying the above principle and shows by dotted lines the driving mechanism underneath the bed;

Fig. 2 is a side elevation of the machine in the direction of the arrow 2 of Fig. 1;

Fig. 3 is a side elevation looking in the direction of the arrow 3 of Fig. 1;

Fig. 4 is a vertical sectional view taken on line 4-4 of Fig. 1 looking in the direction of the arrows, and shows the orifices in the two conveyers alined with the assembling plunger;

Fig. 5 is a vertical sectional view taken at right angles to Fig. 4 along line 5-5 of Fig. 1;

Fig. 6 is a plan view taken along line 6-6 of Fig. 2 showing the cross conveyers as they intersect and lie in the guide slots of the bed of the machine;

50 Fig. 7 is an enlarged sectional view taken on line 7-7 of Fig. 1, looking in the direction of the arrows, showing the can end stack chute and the manner in which the chain passes under it;

Fig. 8 is an enlarged sectional view taken 55 on line 8-8 of Fig. 1 looking in the direction of the arrows, showing the can end liner stack chute and the manner in which the conveyer passes under it.

Fig. 9 is an enlarged detail plan and side 60 view showing one of the link blocks for conveying the can end liners; and

Fig. 10 is an enlarged detail plan and side view showing one of the link blocks 65 for conveying the can ends.

In the embodiment of the invention shown on the drawings reference character A designates a main frame consisting of legs a^1 supporting at its top a bed plate a^2 carrying upon its upper face an auxiliary bed plate 70 a^3 and on its under side the main driving mechanism B. A pair of block chain conveyers C and D are carried also by the bed plate a^2 in suitable tracks c^1 and d^1 and are arranged to move at approximately right 75 angles to each other. These conveyers lie in planes one above the other and have cylindrical apertures d^2 and c^2 which intersect and aline during the operation of the machine. On the auxiliary bed plate a^3 are 80 positioned two stack supports, one consisting of rods c^4 for the can ends and the other of rods d^4 for the liners. The stack support for the can ends is located over the travel of the under conveyer C which selects the can 85 ends from the stack and conveys them to the assembling station as will be later hereinafter described, and the stack support for the liners is similarly located over the upper conveyer which carries the can end liners 90 into assembling position, the auxiliary bed plate a^3 being cut away at a^4 and a^5 beneath the stacks to permit the can ends and can end liners to pass through the auxiliary bed plate a^3 into the apertures in the 95 conveyers. The lower conveyer, which carries can ends, has recesses or pockets in depth equal substantially to the depth of a can end, and the passageway between the bed plate a^2 and the auxiliary bed plate a^3 is so arranged that only a single can end can be selected by each block of the chain conveyer as it passes beneath the stack. The upper conveyer or the one for selecting the can end liners is, however, materially thicker 100 than the thickness of a liner and is provided in its aperture d^2 , which extend through each block, with an inwardly ex-

65

75

80

85

90

95

100

105

tending rib d^3 located just beneath the upper face of the block a distance equal to the thickness of a liner so that the lowermost liner of a stack will seat upon this rib and be carried with the block as it moves from beneath the stack, the upper ones being restrained by the upper bed plate a^2 . A liner and a can end is therefore positioned in each successive hole in the liner and can end conveyers respectively to pass beneath the stacks.

The assembling is done at the point of crossing of the two conveyers, so that each time a filled can end liner opening in the liner carrying conveyer and a filled can end opening in the can end carrying conveyer are in registration the liner is positioned in the can end brought just beneath it. This is accomplished by a reciprocating plunger which descends at each such occurrence. The conveyers advance by a step by step movement and are quiescent between the steps, each step disposing a liner over an unlined can end and each period of quiescence resulting in the deposition of a liner in a subjacent can end. The liner stack and the can end stack are arranged so that a liner opening and a can end opening, respectively, of the conveyers are beneath the stacks at each period of quiescence, this permitting the relatively delicate liners to be seated in successive liner openings in the liner conveyer quietly and accurately and while the conveyers are at rest.

The power for driving these parts is supplied and transferred as will now be described. A main shaft b^1 carrying upon its end a pulley b^2 is journaled in bearings b^3 secured to the under side of the bed plate a^2 . This shaft carries a stud-carrying disk b^4 having a single roller stud b^5 which engages an intermittent gear b^6 and constituting with the intermittent disk b^4 a Geneva movement. The intermittent gear b^6 is mounted upon a shaft b^7 mounted in bearings b^8 upon the under side of the bed plate a^2 . The shaft b^7 carries two sprocket wheels b^9 over which an end of the conveyer D is trained, this conveyer being also trained over two idle sprocket wheels b^{10} at the other side of the frame. The shaft b^7 carries at its end a bevel gear b^{11} which engages a bevel gear b^{12} upon a shaft b^{13} mounted in bearings b^{14} extending downwardly from the bed plate a^2 . This last mentioned shaft has fixed upon it a pair of sprocket wheels b^{15} over which is trained the conveyer C, said conveyer being trained also over sprocket wheels b^{16} , said sprocket wheels b^{16} and the sprocket wheels b^{10} being on shafts i and k , respectively mounted in bearings b^{18} and b^{17} , which are pressed outwardly by springs b^{19} to hold both conveyers taut.

Coöperating locking members b^{20} and b^{21}

are provided, respectively, upon the shafts b^1 and b^7 to insure accurate operation of the Geneva movement. The member b^{20} being a disk having an arcuate depression on one side and the member b^{21} being larger and having a number of arcuate depressions disposed about its periphery. The arcuate depression of each disk being of a curvature to fit the circumference of the other (Figs. 2 and 4).

A reciprocating plunger H is provided, comprising a head h^1 , from which a shaft or stem h^2 extends upwardly through a bearing h^3 in a yoke h^4 positioned upon the top of the upper bed plate a^2 . This plunger receives actuation from a lever h^5 pivoted at one end at h^6 on the stem h^2 and at the other end at h^7 to an eccentric rod h^8 , said lever being fulcrumed near its center at h^9 in an upwardly extending bracket h^{10} . The eccentric connecting rod h^8 embraces an eccentric h^{11} fixed upon the shaft b^1 , movement of the shaft causing thereby a continuous reciprocation of the plunger. The Geneva movement already described and the diameter of the sprockets over which the conveyers are trained, are such that for each actuation through the Geneva movement both conveyers are advanced a space equal to a block, and the parts are so timed with respect to the plunger that each movement occurs when the plunger is in elevated position. The plunger descends between the steps and pressing first upon a liner forces it past the inwardly extending ledge d^3 and down into the can end forming a unitary structure. Thereafter the plunger moves up and when it has cleared the upper conveyer the conveyers advance a step, bringing a new liner and new can end into an assembling position and carrying the lined can end to the discharge station. This station is located in the present instance at the sprockets b^{15} (see Fig. 5). Adjacent the travel of the conveyer around these sprockets are positioned two yielding fingers e^1 which take into slots e^2 (Fig. 10) extending lengthwise of each block of the conveyer for the can ends, and these slots introduce the fingers into the can end openings or pockets and lift the lined can ends out. These fingers are secured in place by a pin e^3 and in passing through the slots lift the lined can ends and cause them to slide down the fingers and drop into a chute e^5 from which they fall onto a delivery conveyer c^4 . The fingers e^1 are sufficiently loose on their pivot to yield as many be required by the movements of the conveyer links, and maintain themselves in the slots e^2 by gravity.

Each conveyer is composed of blocks rectangular or square in cross-section and hinged together at their adjacent edges at

*f*¹. Each block carries a pair of laterally extending lugs *f*² which engage the sprockets already described to insure accurate timing, so that the orifices will properly align 5 after each intermittent movement.

It is thought that the invention and many of its attendant advantages will be understood from the foregoing description, and it will be apparent that various changes may be 10 made in the form, construction and arrangement of the parts without departing from the spirit and scope of the invention or sacrificing any of its material advantages, the form hereinbefore described being merely 15 a preferred embodiment thereof.

I claim:

1. In a machine for applying can end liners to the flanges of shouldered can ends, for the production of interfolded hermetic 20 seams with flanged can bodies, in combination: can end feed mechanism and can end liner feed mechanism comprising intermittently movable endless belt conveyers moving in horizontal planes one above the other, 25 and having an intersecting station where a can end and a can end liner are brought into assembling position, and means for assembling a can end and a can end liner at the said station.

2. In a machine for applying can end liners to the flanges of shouldered can ends, for the production of interfolded hermetic seams with flanged can bodies, in combination: can end feed mechanism and can end 30 liner feed mechanism comprising intermittently movable endless belt conveyers moving in horizontal planes one above the other, and having an intersecting station where a can end and a can end liner are brought into 35 assembling position, and vertically acting means for assembling a can end and a can end liner at the said station.

3. In a machine for applying can end liners to the flanges of shouldered can ends, for the production of interfolded hermetic 40 seams with flanged can bodies, in combination: can end feed mechanism and can end liner feed mechanism comprising intermittently movable endless belt conveyers moving in horizontal planes one above the other, and having an intersecting station where a can end and a can end liner are brought into 45 assembling position, in alinement; vertically movable means for assembling the can end and can end liner at the said station; and means for discharging lined can ends.

4. In a machine for applying can end liners to the flanges of shouldered can ends, for the production of interfolded hermetic 50 seams, with flanged can bodies, in combination: an endless belt conveyer having linear movement and adapted to receive and convey can ends, a second endless belt conveyer having linear movement and adapted to receive and 55 convey can end liners, said conveyers moving at approximately right angles to each other, said conveyers intersecting in their movement whereby a can end and a can end liner are brought into assembling position, one above the other, and within the operative zone of assembling mechanism; and assembling mechanism whereby the said can end and can end liner are assembled as 60 a complete unit.

ceive and convey can end liners, said conveyers intersecting in their movement whereby a can end and a can end liner are brought into assembling position and within the operative zone of assembling mechanism, and assembling mechanism whereby the said can 65 end and can end liner are assembled as a complete unit.

5. In a machine for applying can end liners to the flanges of shouldered can ends, for the production of interfolded hermetic 70 joints, with flanged can bodies, in combination: an endless belt conveyer having linear movement and adapted to automatically receive and convey can ends, a second endless belt conveyer having linear movement and adapted to automatically receive and convey can end liners, said conveyers intersecting in their movement whereby a can end and a can end liner are brought into assembling position and within the operative zone 75 of assembling mechanism; and assembling mechanism whereby the said can end and can end liner are assembled as a complete unit.

6. In a machine for applying can end liners to the flanges of shouldered can ends, for the production of interfolded hermetic 80 seams, with flanged can bodies, in combination: an endless belt conveyer having linear movement and adapted to automatically receive and convey can ends from the bottom of a stack and convey same, a holder for said stack, a second endless belt conveyer having linear movement and adapted to automatically receive can end liners from the bottom of a 85 stack and convey same, a holder for said liner stack, said conveyers intersecting in their movement whereby a can end and a can end liner are brought into assembling position and within the operative zone of 90 assembling mechanism; and assembling mechanism whereby the said can end and can end liner are assembled as a complete unit.

7. In a machine for applying can end liners to the flanges of shouldered can ends, for the production of interfolded hermetic 95 seams, with flanged can bodies, in combination: an endless belt conveyer having linear movement and adapted to receive and convey can ends, a second endless belt conveyer 100 having linear movement and adapted to receive and convey can end liners, said conveyers moving at approximately right angles to each other, said conveyers intersecting in their movement whereby a can end and a can end liner are brought into assembling position and within the operative zone of 105 assembling mechanism; and assembling mechanism whereby the said can end and can end liner are assembled as a complete unit.

8. In a machine for applying can end liners to the flanges of shouldered can ends, 110

115

120

125

for the production of interfolded hermetic seams, with flanged can bodies, in combination: an endless belt conveyer having intermittent linear movement and adapted to receive and convey can ends, a second endless belt conveyer having intermittent linear movement and adapted to receive and convey can end liners, one conveyer having movement at an angle to the other, said conveyers intersecting in their movement whereby a can end and a can end liner are brought into assembling position and within the operative zone of assembling mechanism; and assembling mechanism whereby the said can end and can end liner are assembled as a complete unit.

9. In a machine for applying can end liners to the flanges of shouldered can ends, for the production of interfolded hermetic seams with flanged can bodies, in combination: an endless belt conveyer having linear movement adjacent a stack of can ends, and adapted to receive ends from said stack, a holder for said stack, a second endless belt conveyer having linear movement, adjacent a stack of can end liners, and adapted to receive liners from said stack, a holder for the stack of liners, said conveyers intersecting in their movement whereby a can end and a can end liner are brought into assembling position and within the operative zone of assembling mechanism; and assembling mechanism whereby the said can end and can end liner are assembled as a complete unit.

10. In a machine for applying can end liners to the flanges of shouldered can ends, for the production of interfolded hermetic seams with flanged can bodies, in combination: an endless belt conveyer having linear movement, adjacent a stack of can ends, and adapted to receive ends from the bottom of said stack, a holder for said stack, a second endless belt conveyer having linear movement, adjacent a stack of can end liners, and adapted to receive liners from said stack, a holder for said stack of liners, said conveyers intersecting in their movement whereby a can end and a can end liner are brought into assembling position, and assembling mechanism whereby the said can end and can end liner are assembled as a complete unit.

11. In a machine for applying can end liners to the flanges of shouldered can ends, for the production of interfolded hermetic seams with flanged can bodies, in combination: an endless belt conveyer having linear movement, adjacent a stack of can ends, and adapted to receive ends from said stack, a holder for said stack, a second endless belt conveyer having linear movement, adjacent a stack of can end liners, and adapted to receive liners from the bottom of said stack, a holder for said stack of liners, said con-

veyers intersecting in their movement whereby a can end and a can end liner are brought into assembling position, and assembling mechanism whereby the said can end and can end liner are assembled as a complete unit.

12. In a machine for applying can end liners to the flanges of shouldered can ends, for the production of interfolded hermetic seams with flanged can bodies, in combination: an endless belt conveyer having linear movement, adjacent a stack of can ends, and adapted to receive ends from the bottom of said stack, a holder for said stack, a second endless belt conveyer having linear movement, adjacent a stack of can end liners, and adapted to receive liners from the bottom of said stack, a holder for said stack of liners, said conveyers intersecting in their movement whereby a can end and a can end liner are brought into assembling position, and assembling mechanism whereby the said can end and can end liner are assembled as a complete unit.

13. In a machine for applying can end liners to the flanges of shouldered can ends, for the production of interfolded hermetic seams with flanged can bodies, in combination: an endless belt conveyer having linear movement, adjacent a stack of can ends, and adapted to automatically receive ends from the bottom of said stack, a holder for said stack, a second endless belt conveyer having linear movement, adjacent a stack of can end liners and adapted to automatically receive liners from the bottom of said stack, a holder for said stack of liners, said conveyers intersecting in their movement whereby a can end and a can end liner are brought into assembling position, and assembling mechanism whereby the said can end and can end liner are assembled as a complete unit.

14. In a machine for applying can end liners to the flanges of shouldered can ends, for the production of interfolded hermetic seams with flanged can bodies, in combination: an endless belt conveyer having intermittent linear movement, adjacent a stack of can ends, and adapted to receive ends from said stack; a holder for said stack; a second endless belt conveyer having intermittent linear movement, adjacent a stack of can end liners, and adapted to receive liners from said stack, a holder for said stack of liners; said conveyers intersecting in their movement whereby a can end and a can end liner are brought into assembling position, and assembling mechanism whereby the said can end and can end liner are assembled as a complete unit, and means for discharging the lined can ends.

15. In a machine for applying can end liners to the flanges of shouldered can ends, for the production of interfolded hermetic

seams with flanged can bodies, the combination of an endless conveyer movable past an assembling point for conveying can ends, and an endless conveyer movable over said 5 first mentioned conveyer at said assembling point for conveying can end liners, one of said conveyers being flexible, and means for assembling said liners on said can ends located at said assembling point, and operating 10 through one of said conveyers and against the other conveyer.

16. In a machine for applying can end liners to the flanges of shouldered can ends, for the production of interfolded hermetic 15 seams with flanged can bodies, the combination of a pair of endless conveyers, one of which is flexible, the operative travel of said conveyers being disposed one above the other and crossing at an assembling station, 20 said conveyers being adapted respectively to convey can ends and can end liners to said assembling station and each being provided with means for accurately alining said can ends and can end liners at said assembling 25 station, and means for assembling said can ends and can end liners.

17. In a machine for applying can end liners to the flanges of shouldered can ends, for the production of interfolded hermetic 30 seams with flanged can bodies, the combination of an endless conveyer having recesses adapted to receive the can ends to be alined, a second endless conveyer having recesses adapted to aline with the recesses of said 35 first mentioned conveyer and to support gasket liners, one of said conveyers being flexible, and means for assembling said liners and can ends, and a fixed support for the flexible conveyer at the assembling station.

40 18. In a machine for applying can end liners to the flanges of shouldered can ends, for the production of interfolded hermetic seams with flanged can bodies, the combination of a can end feed mechanism and can 45 end liner feed mechanism, each having recessed seats and a straight line movement one above the other and toward the assembling station, and means for assembling said can ends and can end liners at said assembling 50 station.

19. In a machine for applying can end liners to the flanges of shouldered can ends, for the production of interfolded hermetic 55 seams with flanged can bodies, the combination of a can end feed mechanism and can

end liner feed mechanism, each having a straight line intermittent progressive movement one above the other and toward the assembling station, and vertical acting means for assembling a can end liner directly on the can end at said assembling 60 station.

20. In a machine for applying can end liners to the flanges of shouldered can ends, for the production of interfolded hermetic 65 seams with flanged can bodies, the combination of a device for holding a stack of can ends, a device for holding a stack of can end liners, an endless conveyer for automatically removing can ends successively from said can end stack, an endless conveyer for automatically removing can end liners from said can end liner stack, said conveyers having progressive straight line movement and carrying said liners and 70 can ends to an assembling station, and means for assembling said liners on said can ends.

21. The combination of two endless belt conveyers one having a limb superposed on a limb of the other, the upper conveyer having spaced apertures for carrying ring liners and adapted for the passage of the ring liners therethrough, and the lower conveyer having spaced means for holding can ends, 85 means for actuating said conveyers intermittently and in unison, and an assembling device operating through the apertures of the upper conveyer and into the can ends on the lower conveyer. 90

22. The combination of two rectilinear conveyers arranged in close proximity to each other, one of said conveyers having spaced perforations adapted to carry ring liners and the other of said conveyers having spaced means for holding and carrying can ends, actuating mechanism for moving said conveyers intermittently and causing one of said perforations to register with one of said can end holding means at the 95 intervals of rest, and assembling means adapted to operate through said perforations and into said can ends.

In testimony whereof I have hereunto set my hand in the presence of two subscribing 105 witnesses.

CHARLES W. GRAHAM.
